UNITED STATES PATENT OFFICE.

ALBA NEVIS, OF NEW YORK, N. Y.

PROCESS FOR ORNAMENTING VELVET AND THE LIKE.

Application filed December 27, 1923. Serial No. 682,879.

This invention relates to ornamenting velvet and similar textile fabrics by the so called "burning" method and to a process for quickly and inexpensively copying the 5 ornaments of an original on other pieces of velvet or similar fabrics by mechanical means.

The main object of this invention is to provide a process whereby such ornamented 10 fabrics may be produced in practically unlimited numbers with very little cost showing a true copy of the original artistic model.

Incidentally my invention also provides improved means for producing the original 15 first copy of such ornamented fabrics and for copying the same in great numbers by cheap mechanical means.

With the above and other objects in view my invention mainly resides in "burning" 20 embossed designs in velvet fabrics by an appropriate tool, coloring said designs and "burning" them again till the desired artistic effect is obtained in the original copy, in providing means to transfer said copy 25 onto a metal plate, preferably brass or bronze, heating said plate and pressing its embossed design into new pieces of velvet when in a heated condition, coloring the copies of the original so produced, re-heating 30 the plate and again submitting the colored copies to pressure under said heated plate, until an artistic product is obtained showing the embossed design and the glossy surface and coloring of the original.

The foregoing and other objects of the invention, together with means whereby the same may be carried into effect will be best understood from the following description 35 of certain forms or embodiments thereof, illustrated in the accompanying drawings. It will be understood, however, that the particular constructions described and shown, have been chosen for illustrative purposes merely, and that the invention, as 40 defined by the claims hereunto appended, may be otherwise practised, without departing 45 from the scope or spirit thereof.

In the drawings:—

Fig. 1 is a plan view of a piece of velvet 50 showing an artistic design thereon "burned" by my "burner,"

Fig. 2 is a longitudinal sectional view of a "burner" adapted to be used in my novel process;

Figs. 3 and 4 are front and rear elevational views, respectively, of the same, while

Fig. 5 is a fragmental plan view of the adjusting device of said "burner," and

Fig. 6 is a cross sectional view of the metallic plate used in reproducing the design 60 shown in Fig. 1.

Referring more closely to the drawings the numeral 7 indicates a piece of velvet or other textile fabric of similar characteristics, having relatively long glossy fibers on the one side of the same. On the long fibered side of the velvet I now copy the design to be "burned" therein, as at 8, by any appropriate method and then proceed to "burn" 70 the same into the fabric using any appropriate so called hot-point tool, preferably the one illustrated in Figures 3 to 5 and described hereinafter.

Said tool consists of a tubular container and handle 9 showing a valve body 10 secured to it at the one end of the same while the other end is closed by the screw threaded means 11. Tubular channel 12 is drilled through the center of valve body 11 and is in connection with the "burner" head proper 75 13 which shows a small opening 14 in the center of its closing wall 15. A holder piece 16 is secured on the "burner head" 13 showing a hole 17 in the upper portion of it into which "burning irons" 18 of different sizes 80 and shapes may be inserted and secured by the screw 19. The "burning irons" are preferably and conveniently made of pieces of copper wire flattened and doubled at their appropriately bent working ends 20. A 90 conical valve 21 is inserted into valve body 10 and secured therein, preferably by the spring means 22 having the usual nubbed grip disk 23 and limiting pin 24 co-operating 95 therewith.

The use and operation of this burner tool is as follows: The space 25 is filled with ether, or other easy flowing and evaporating combustible liquid, valve 21 turned into the open position and the combustible vapors 100 emitted through the minute opening 14, lighted. The flame will heat the "burning iron" 20 to the desired degree, depending on the adjustment of valve 21 and also on the amount of liquid contained in the space 105 25, and it may be manipulated over the design 8 on velvet piece 7 and the fibers subjected to heat and pressure in a skillful manner. The fibers will by this operation be firmly pressed to the groundwork of the fabric, under heat and pressure, in fact so firmly 110 as to cause adhesion, producing glossy and

shining, more or less depressed, surfaces and abrupt ridges, following the design, and "burning" the same into the velvet in this manner.

5 After the design is "burned" into the piece of fabric, it is colored according to the instructions of the designing artist, by any suitable means, the air brush system being preferred on account of the uniform tone of 10 the colors produced and the speed in the execution of the work.

The colored design is again worked over or "burned" in with the same tool as described hereinbefore, so that the colors will firmly adhere to the fibers and a glossy attractive surface produced. In order to mechanically reproduce this design, I now copy 15 the same on a brass or bronze plate 26 by any of the standard methods, truly following not only the outlines of the design but its relative depressions, ridges, elevations and recesses. The design naturally is copied on the plate in a negative manner, that is, the 20 plate will show a projection where the original design has a recess, and vice-versa.

I now place this plate into a press of suitable make and apply the piece of velvet to which said design is to be imparted, on the 25 plate, previously heating the plate to the necessary temperature. The design is thereupon pressed into the new piece of fabric and by repeated heating of the plate and application of new pieces of fabric in the press any desired number of copies may be prepared. The copies thus produced are thereupon colored in a similar manner as the 30 original model was prepared, the plate reheated and the colors pressed into the design.

40 By the process thus described I not only am able to produce exceptionally attractive designs on velvets and similar fabrics but can reproduce them in unlimited numbers with the same degree of perfection as the 45 original was done and in an inexpensive manner.

I also discovered that the appearance of my pressed velvet pieces may be greatly improved, and their colors and glossy surface 50 made waterproof by coating my plate with a small amount of paraffin and pressing it in such condition a second time over the embossed and colored design.

The plate is in all cases intended to be an 55 exact negative of the design initially produced on the velvet. Thus the depth of the

lines produced on the velvet in course of forming the design thereon is reproduced in the form of corresponding elevated ridges on the plate. Where the depth of the lines is 60 less, the height of the corresponding ridges varies accordingly.

Various expedients can be resorted to whereby the reproduction of the design on said plate can be facilitated. Wax engraving methods can be used, in conjunction with the usual electrolytic methods of forming a metal plate. Preferably, I may photograph the design upon a photo-sensitized plate. The plate is then cut into, the eye of the 70 skilled operator serving to guide him to produce ridges on the plate varying point by point as the depth of corresponding lines in the velvet.

What I claim as new is:—

1. A process for burning ornaments into 75 velvet or similar textile fabrics, consisting in copying the design of said ornaments on the long fibered side of a piece of such materials, following said design by a heated pressing tool and sinking it into said piece of material, making a negative copy of the ornamentation of said piece of material on a metallic plate, heating said plate and pressing its design into a desired number of pieces 80 of similar materials, coloring said pieces and again submitting them to the pressure of the 85 heated plate.

2. A process for burning ornaments into 90 velvet or similar textile fabrics, consisting in copying the design of said ornaments on the long fibered side of a piece of such materials, following said design by a heated pressing tool and sinking it into said piece of material, making a negative copy of the 95 ornamentation of said piece of material on a metallic plate, heating said plate and pressing its design into a desired number of pieces of similar materials, coloring said pieces, heating said plate, coating the same with a 100 small amount of paraffin and again pressing it on said embossed and colored ornamentation.

3. A pile fabric having a design impressed 105 therein so as to exhibit sheen in the impressed portion having colors applied thereto, said colors being waterproofed by a layer of paraffin pressed thereon.

Signed at New York, in the county of New York and State of New York this 22nd day 110 of September, A. D. 1923.

ALBA NEVIS.
